(57) **CLAIM**

The ornamental design for a bracket for container as shown and described.

DESCRIPTION

FIG. 1 is a top perspective view of a bracket for container showing my new design, with a container shown in broken lines;

FIG. 2 is a top perspective view thereof;

FIG. 3 is a bottom perspective view thereof;

FIG. 4 is a front view thereof;

FIG. 5 is a right side view thereof;

FIG. 6 is a rear view thereof;

FIG. 7 is a left side view thereof;

FIG. 8 is a top view thereof; and,

FIG. 9 is a bottom view thereof.

The broken lines shown in the figures show portions of the bracket for container and environment that form no part of the claimed design.

1 Claim, 7 Drawing Sheets
